UNITED STATES PATENT OFFICE.

FRANK E. BURCHFIELD, OF DERBY, CONNECTICUT, ASSIGNOR TO SHELTON TOOL & MACHINE CO., OF SHELTON, CONNECTICUT, A CORPORATION.

DESIGN FOR A FORK.

55,589.

Specification for Design.

Patented July 6, 1920.

Application filed November 14, 1919. Serial No. 338,122. Term of patent 7 years.

To all whom it may concern:

Be it known that I, **FRANK E. BURCHFIELD**, a citizen of the United States, residing at Derby, in the county of New Haven and State of Connecticut, have invented a new, original, and ornamental Design for a Fork, of which the following is a specification, reference being had to the accompanying drawing, forming part thereof.

Figure 1, a face view of a fork showing my design.

Fig. 2, a sectional view on the line 2—2 of Fig. 1.

Fig. 3 a sectional view on the line 3—3 of Fig. 1.

Fig. 4, a sectional view on the line 4—4 of Fig. 1.

Fig. 5, a sectional view on the line 5—5 of Fig. 1.

Fig. 6, a sectional view on the line 6—6 of Fig. 1.

I claim:

The ornamental design for a fork, as shown.

In testimony whereof, I have signed this specification in the presence of two subscribing witnesses.

FRANK E. BURCHFIELD.
